UNITED STATES PATENT OFFICE.

ADOLPH L. BERNHEIMER, OF NEW YORK, N. Y.

DESIGN FOR WOVEN FABRIC.

SPECIFICATION forming part of Design No. 31,662, dated October 10, 1899.

Application filed September 1, 1899. Serial No. 729,254. Term of patent 31 years.

To all whom it may concern:

Be it known that I, ADOLPH L. BERNHEIMER, a citizen of the United States, residing at New York, in the borough of Manhattan and State 5 of New York, have invented and produced a new and original Design for Woven Fabrics, of which the following is a specification, reference being had to the accompanying drawing, forming part thereof.

10 The drawing represents sufficient of a piece of woven fabric to illustrate the design.

As shown in the drawing, the leading or material feature of my design consists of a series of broad stripes A, alternating with 15 groups B, of very narrow stripes, the field of each broad stripe B having arranged thereon a

number of double bows C C'. The bows C are set at an angle to the bows C', and all the bows are arranged in parallel diagonal lines.

Having described my invention, what I 20 claim as new, and desire to secure by Letters Patent, is—

The design for a woven fabric as herein shown and described.

In testimony that I claim the foregoing as 25 my invention I have signed my name in presence of two subscribing witnesses.

ADOLPH L. BERNHEIMER.

Witnesses:

M. H. WURTZEL,
PAUL GOEPEL.
